WELL HOLE CLEANER AND METHOD

Isaac L. Ault, Morgan City, La., assignor to Houston Oil Field Material Company, Inc., Houston, Tex., a corporation of Delaware

Filed Sept. 30, 1957, Ser. No. 687,224

6 Claims. (Cl. 166—43)

The present invention relates to apparatus for and a method of cleaning the pipe fails surrounding the annular space between the tubing and the casing in a well bore, and, more particularly, relates to such apparatus and methods in which the apparatus is moved between the tubing and casing by the application of fluid pressure against it thereby loosening the debris and cleaning the exposed walls of the tubing and of the casing.

In the normal operation of an oil well, the space or annulus between the tubing and the casing becomes caked with dirt, drilling mud, and other material, commonly referred to as "junk" in the trade. Considerable difficulty has been encountered in cleaning the tubing and casing walls that enclose this annular space so that the well might function as intended.

It is an object of this invention to provide an improved apparatus and method for loosening, cleaning and removing the junk from between the tubing and casing in a well bore.

A further object of the present invention is the provision of an improved apparatus adapted to be introduced into the annular space between the casing and tubing of a well bore and, in response to pump pressure, be moved in this space thereby cleaning and loosening the exposed pipe walls of junk.

Yet a still further object of the present invention is the provision of an improved apparatus for cleaning and removing debris and junk from between the casing and tubing in a well bore and which includes means responsive to fluid pressure so that it may be pumped downwardly in the annular space between the casing and the tubing and by reversing circulation may be pumped upwardly in the annular space thereby dislodging, cleaning and pushing the junk out from between the casing and the tubing.

Yet a further object of the present invention is the provision of such an improved apparatus or, as commonly referred to in the trade, a junk pusher, which is simple, efficient and economical to use, construct and maintain.

Yet a further object of the present invention is the provision of a method of cleaning the junk or debris collected in the annular space between the tubing and casing in a well bore by inserting an annular cleaner provided with a pressure-responsive element into this space and applying fluid pressure against the pressure-responsive element thereby moving the cleaner and cleaning the junk from between the casing and the tubing.

Yet a further object of this invention is the provision of an improved method of cleaning junk which includes inserting an annular cleaning assembly into the annular space between the casing and tubing in a well bore and pumping it down this space and thereafter reversing circulation and pumping it up the space to dislodge and clean the junk or debris collected in the annular space.

Other and further objects, features and advantages

will be apparent from the following description of a presently preferred embodiment of the invention, given for the purpose of disclosure, and taken in conjunction with the accompanying drawing, where like character references designate like parts throughout the several views and where,

Figure 1 is an elevational view, in quarter section, illustrating an apparatus according to the invention in position between the tubing and casing ordinarily disposed in a well bore, and

Figure 2 is a cross-sectional view taken along the line 2—2 of Figure 1.

Referring now to the drawings, and particularly to Figure 1, the reference numeral 10 generally designates the well hole cleaner which includes a central ring-like body section 14, which might be termed the packer or piston section of the tool. This section 14 has an annular, resilient packer 16 secured to its outer surface and an annular, resilient packer 17 secured to its inner surface. It is noted that these packers are of the cup-type packers so that means are provided which will enable the cleaner to respond to pump pressure applied either to the upper or lower areas of the packers 16 and 17. Of course, any preferred pressure responsive means may be used so that the well cleaner 10 may respond to and be pumped up and down in the annular space 19 between the casing 18 and the tubing 20 disposed in the well bore, not shown. The packers 16 and 17 may be secured to the central body section 14 in the recessed portions 13 and 15 provided to receive them in any preferred manner. It is noted that the packers 16 and 17, in effect, form an annular, resilient piston against which fluid pressure is directed to move the cleaner 10 in the annulus 19.

Secured to each end of the central body section 14 are a pair of ring-like, elongated body sections 12a and 12b. These are the scraper and wiper sections of the cleaner 10. As illustrated, these sections may be threaded to the central body section 14, although they may be secured thereto in any preferred manner. For convenience of manufacture, the body sections 12a and 12b are identical and may be interchanged.

For convenience of reference, identical numbers are applied to both of these sections except that the reference letter "a" has been added to the numbers in the upper section and the reference letter "b" has been added to the reference numerals in the lower section. Accordingly, in describing these sections, reference will be made to the upper section, but it will be understood that the lower section is identical and utilizes the same reference numerals with the exception that the reference letter "b" has been substituted for the reference letter "a."

Turning now to the upper scraper section, a plurality of elongate wiper or scraper elements 24a are circumferentially spaced about the body section 12a and are inwardly directed and yieldingly engage the outer surface of the tubing 20. These wiper or scraper sections 24a extend axially a substantial length of the scraper section 12a. Similarly, a plurality of circumferentially-spaced scraper or wiper elements 28a extend outwardly from the body 12a and yieldingly engage the inner surface of the casing 18, as best seen in Figure 2. Preferably, the inner scraper or wiper elements 24a and outer wiper elements 28a are circumferentially staggered in alternate relationship so that the scraper or wiper elements perform the dual function of scraping and wiping the tubing and casing and of maintaining the junk cleaner 10 in a generally aligned position with respect to the tubing 20 and casing 18.

A plurality of axially extending slots or pockets 22a

and 26a receive the elongate wipers or scrapers 24a and 28a, respectively, and a plurality of springs 29a and 30a are provided in the pocketed portions of the scrapers 24a and 28a so that these scrapers are yieldingly urged into engagement with the exposed surfaces of the tubing 20 and casing 18, as previously described.

In order to retain the scrapers 24a and 28a in the slots 22a and 26a, respectively, the stop rings 36a are welded or otherwise secured to the lower portion of the scraper section 12a and a stop ring 38a is threadedly secured to the upper end of this section, such as by the bolts 40. The projections or ears 35a are provided on each end of the scraper or wiper segments 24a and engage under the projecting shoulders of the stop members 36a and 38a, respectively.

In connection with the outer scraper elements 28a, these are shown in the lower section to which the reference letter "b" has been applied. It is noted that the retaining means for the outer scraper elements 28a are in all things identical to those described in connection with the inner scraper or wiper segments 24a. Accordingly, no further description thereof is deemed necessary. The stop members 34a and 37a, however, for these segments are illustrated in the upper portion of Figure 1. It is noted that the stop ring 37a is welded to the upper scraper body member 12a and the stop ring 34a is a continuation of the upper cap 32a which is threadedly secured to the upper end of the upper body section 12a.

As mentioned previously, the lower wiper or scraper section 12b is constructed identically to that of the top section except that preferably the scraper sections are reversed or staggered with respect to the upper scraper section so that substantially complete circumferential cleaning or scraping is accomplished.

It is noted that the scraper or wiper sections advantageously perform several functions. Since they are alternately spaced on the scraper body sections, they align the cleaner in the annulus 19. In addition, they permit considerable flexibility so that the cleaner will pass in many places which are not concentric, or which are restricted and the like. These scraper sections also provide a cleaning and scraping action on the accumulated junk between the casing and the tubing and provide substantially circumferential cleaning. If desired, of course, the wiper or scraper elements may be disposed at an angle to the axis of the tool, however, highly advantageous results have been obtained by the structure illustrated.

In use, the well cleaner 10 is placed in the annular space 19 between the casing 18 and tubing 20. Fluid pressure, such as by pumps, is directed downwardly against the well cleaner 10 which forces the cleaner 10 downwardly in the annular space thereby scraping and cleaning the exposed walls of the casing 18 and tubing 20, the packers 16 and 17 serving as a pressure responsive means or annular piston. After bottom has been reached, the circulation is reversed so that fluid is pumped down the tubing and back up through the annular space 19 which causes or forces the well cleaner 10 to be moved up the annular space 19. During such movement, of course, the exposed walls are again scraped and cleaned and the junk is pushed ahead of the well cleaner.

Ordinarily, a pressure indicating device, not shown, is used in connection with the pumps and a sharp rise in pressure indicates when bottom and top is reached or when the cleaning tool is in danger of becoming stuck.

It is noted that the center or packer section provides a resilient seal in the annulus 19 and serves as a flexible piston so that the cleaner 10 moves in response to pump pressure directed either to the upper part of the piston or the lower part thereof. This flexible annular piston and seal is sufficiently resilient to permit the tool to pass through restrictions in the annulus, such as caused by a pipe joint 42. It should be noted also, that the annular packer or flexible piston aids in the cleaning of the an-

nulus by rubbing against the exposed walls of the casing 18 and tubing 20 and by serving to accumulate and carry along the loosened junk.

It will be understood that the cleaning tool 10 includes the omission of one of the cleaning or scraper sections. With only one such section, satisfactory scraping and cleaning may be performed. It will be understood, however, of course, that any number of scraper and packing sections may be used, as desired.

It is believed that the method of the invention is apparent from the foregoing description of a presently-preferred apparatus of the invention. The method, however, comprises the steps of introducing an annular cleaning assembly in the annular space between the casing and tubing, or other pipes, in a well bore, the cleaner assembly having a pressure responsive element, and directing fluid pressure against the pressure responsive element thereby moving the cleaner assembly in the annular space thereby scraping and cleaning debris from the walls thereof.

The method also comprehends pumping, such as applying pump pressure to the fluid in the annular space, the cleaner assembly down the annular space and reversing circulation by pumping fluid down the tubing and directing it to the underside of the cleaner assembly thereby 25 by pumping it up the annular space to perform the cleaning function and to remove the cleaner and debris from the well bore.

The present invention, therefore, is well adapted to carry out the objects and attain the ends and advantages 30 mentioned as well as others inherent therein. While a presently preferred embodiment of the invention is given for the purpose of disclosure, numerous changes in details of construction, arrangements of parts and steps of the process may be made which will readily suggest themselves to those skilled in the art which are encompassed within the spirit of the invention and the scope of the appended claims.

What is claimed is:

1. Apparatus for cleaning the exposed walls between 40 coaxially disposed pipes in a well bore comprising, an elongate annular body adapted to be moved between said pipes, pressure-responsive means secured to the body and adapted to engage the walls of the pipes, a plurality of scraper elements yieldingly secured to the body and adapted to engage exposed walls of the pipes, and means connected to said pipes for applying fluid pressure between said pipes whereby application of fluid pressure to the pressure-responsive means moves said apparatus thereby scraping said exposed walls.

2. Apparatus for cleaning the walls surrounding the annulus between pipes disposed in a well bore comprising, an elongate annular body adapted to be moved in the annulus, a resilient packer mounted and arranged on said body so as to engage the walls of the pipes, a plurality of scraper elements yieldingly secured to the body and adapted to engage exposed walls of the pipes, and means connected to said pipes for applying fluid pressure between said pipes whereby application of fluid pressure to said packer moves said apparatus in the annulus thereby cleaning said exposed walls.

3. Apparatus for cleaning the walls between pipes in a well bore comprising, an elongate annular body adapted to be moved longitudinally between said pipes, said body having a plurality of longitudinally-extending and circumferentially-spaced slots, scraper elements yieldingly secured in said slots and adapted to engage and scrape exposed surfaces of said pipes, a resilient annular piston secured to said body and adapted to engage the exposed walls of said pipes, and means connected to said pipes for applying fluid pressure between said pipes whereby application of fluid pressure against said annular piston moves said apparatus thereby scraping said exposed walls.

4. Apparatus for cleaning the walls surrounding the annulus of pipes disposed in a well bore comprising, an

elongate annular body adapted to be moved in the annulus, said body provided on its outer and inner surfaces with a plurality of longitudinally-extending and circumferentially-spaced slots, said slots on the inner surface being circumferentially staggered with respect to those on the outer surface, a plurality of scrapers yieldingly secured in said slots and adapted to engage exposed walls of said pipes, an annular resilient packer secured to said body and mounted and arranged for engaging said exposed walls, and means connected to said pipes for applying fluid pressure between said pipes whereby application of fluid pressure against said packer moves said apparatus in said annulus thereby scraping and cleaning said exposed walls.

5. Apparatus for cleaning the walls surrounding the annulus of pipe disposed in a well bore comprising, an elongate annular body adapted to be inserted into and moved in the annulus, an annular piston secured to the central portion of said body for engaging exposed walls of said pipes, a scraper assembly secured to the body 20 on each side of said central portion, each said scraper assembly provided with a plurality of alternate inwardly and outwardly extending slots spaced circumferentially about the body, a scraper element yieldingly secured in each slot and yieldingly engaging said exposed walls, 25 and means connected to said pipes for applying fluid pressure between said pipes whereby application of fluid pressure to said annular piston moves said apparatus in

said annulus thereby scraping and cleaning the exposed walls.

6. The method of cleaning debris from the inner wall of casing in a well bore and the outer wall of tubing disposed within the casing, said inner wall and outer wall defining an annular space comprising, inserting an annular cleaner into said annular space engaging the inner and outer walls, applying fluid pressure above and to said cleaner through said annular space thereby moving said cleaner downwardly in said annular space and cleaning the walls, and then applying fluid pressure through the tubing and into the annular space below the accumulated debris and to the bottom of said cleaner thereby moving the cleaner and the accumulated debris upwardly in said annular space to the surface of the well.
